UNITED STATES PATENT OFFICE.

LEWIS L. DOLLINGER, OF ROCHESTER, NEW YORK.

AIR-FILTER.

1,359,879.

Specification of Letters Patent. Patented Nov. 23, 1920.

Application filed June 23, 1920. Serial No. 391,232.

To all whom it may concern:

Be it known that I, LEWIS L. DOLLINGER, a citizen of the United States, residing at Rochester, in the county of Monroe and State of New York, have invented certain new and useful Improvements in Air Filters, of which the following is a specification.

The object of this invention is to provide a filter that will take all the solid matter out of the air and leave the air free from solid matter, abrasives, etc., so that the air will not carry such materials into the cylinders of an internal combustion engine or air compressor. It is also capable of a variety of other uses as well.

Another object of the invention is to make the filter of comparatively small volume but with a large area of filtering surface.

These and other objects of the invention will be fully illustrated in the drawings, described in the specification and pointed out in the claims at the end thereof.

In the drawings, Figure 1 is a perspective view of the filter, ready to be connected up with the intake of a carburetor or other opening.

Fig. 2 is a horizontal section through the filter on the line 2^x—2^x of Fig. 1.

Fig. 3 is a vertical section on the line 3^x—3^x of Fig. 2.

Fig. 4 is a diagrammatic view showing the placing of the filter on the car with reference to the intake of the carburetor and the manifold and the radiator.

In the drawings, like reference numerals indicate like parts.

In the drawings, reference numeral 1 indicates the cylinder made preferably of a metal shell with a large number of comparatively small perforations therein, which perforations are preferably arranged in a series of parallel rows for a purpose that will presently appear. The ends of the cylinder are closed by the heads 2 and 3, which heads are also perforated with larger openings as shown in Figs. 1 and 2, the openings at the outer edge of the heads being larger than the openings near the center. The head 3 has a large opening centrally thereof, fitted with a sleeve 4, which makes a close joint with the head 3. This sleeve extends into the inside of the drum and forms a flange for holding the several parts in position. On the head 2 is provided a sleeve 5 which also forms a flange for the

holding of the parts in place. Between the two heads is supported the serpentine web 6 of wire mesh which is bent to an outline shown in cross section in Fig. 2. The inner bends of this screen are fastened to the sleeve 7 at one end and to the sleeve 8 at the other end, by which they are held firmly in place. The sleeve 7 is engaged by the sleeve 4 on the head 3 and the sleeve 8 is engaged by the sleeve 5 on the head 2, so that when the two heads are in position the serpentine strip of wire screen is held firmly in position concentric with the shell or cylinder 1. The serpentine strip of wire screen is covered with a cloth made up of a series of pockets so as to make a close fit therewith and conform to the outline thereof, as shown in Fig. 2. As viewed from the outside, this filter forms a series of outwardly opening pockets and as viewed from the inside, it forms a series of inwardly opening pockets. The pockets stand radially in either case and are wedge shaped and the filter has the form of a spider.

At each end and surrounding the sleeves 4 and 5 are provided heavy felt washers 9 and 10, which are interposed between the ends of the screen and the heads, making a dust proof joint between them. These washers also center the screen midway between the two heads so that the air can circulate between each head and the adjacent end of the screen.

In practice, the sleeve 4 is coupled with a suction tube that leads to the air intake of the carburetor, etc., and the air is drawn from the inside of the filter and the air is then drawn through the cloth filtering material which is preferably of wool felt, a large surface of which is exposed. This felt strains out any dust or solid matter that may be in the air at that time. The air is in turn drawn through the openings in the cylinder 1 and the heads 2 and 3. The openings in the cylinder and heads are opposite the outwardly opening pockets in the filter so that the air current is drawn centrally into the outwardly opening pockets and transversely through the filtering material. The velocity of the air through the filtering material and in the outwardly opening pockets is only one-fourth or one-fifth of what it is when it passes through the openings in the cylinder and there will, therefore, be an opportunity for the dust to precipitate on the lower head

and pass through the openings in the lower head.

It will be understood that the carrying capacity of the air current varies approximately directly as the sixth power of the velocity of the current; that is, as regards the weight of the particles carried, and when the velocity is greatly reduced as it will be by the arrangement of my filter, the solid matter in the air will readily separate itself by gravity from the air and what still remains will be taken out by the filter.

After the air has passed through the filter, it is in the inwardly opening pockets, all of which communicate with the central opening of the filter so that the air quickly flows to the exhaust opening, practically free from dirt.

It will be noticed that the metal cylinder has no perforations opposite the ends of the inwardly opening pockets so that the inrush of air through the openings of the cylinder cannot directly strike the ends of the pockets but must go into the outwardly opening pockets and must go into these pockets centrally and then moves sidewise to the filtering surface at a low velocity, permitting the heavy solid matter to separate itself from the air while its velocity is being reduced or retarded in the pockets. It will also be understood that the dust is not forced into the filtering material by any high velocity but rests on it lightly due to the low velocity with which it is carried to the filtering surface and the large area of the filtering surface and from the filtering surface it is, therefore, easily shaken off by the vibration of the machine, if any, so that it drops to the bottom of the filter and out through the openings. This makes the filter practically self cleaning, especially where it is used in automobiles, trucks, tractors, etc.

In Fig. 4, I have shown the filter connected to the carburetor by a tube 10^a, the intake manifold being indicated by the numeral 11 and the position of the radiator being indicated by 12. The filter in this instance is located at the rear of the engine hood and at the top and out of the path of any air current or draft which will interfere with the precipitation of dust. It is also located in a place where it receives the heat of the engine which keeps the filter warm and dry and furnishes warm air as well as clean air to the engine and in this way dispenses with the need of a stove which is usually used on the exhaust pipe of the engine.

I claim:

1. An air filter having a cylindrical shell, openings through said shell arranged in parallel rows, a filter inside of said shell having outwardly opening pockets in line with said rows of holes, said filter being independent of and separate from the cylindrical shell.

2. An air filter having a cylindrical shell with a head at each end thereof, a filter within said shell having a series of inwardly opening pockets covered with filtering material, arranged radially around central cylindrical openings in the ends of the filter, an opening in one head having a sleeve extending therethrough engaging with one of said openings in the filter.

3. An air filter having a serpentine strip of wire screen bent at both ends to form inwardly opening wedge shaped pockets, arranged radially around a cylindrical chamber, cylindrical collars at each end of said chamber to which the folds of the wire screen are attached, a cover of filtering material over all of said pockets.

4. An air filter having a serpentine strip of wire screen bent at both ends to form inwardly opening wedge shaped pockets, arranged radially around a cylindrical chamber, cylindrical collars at each end of said chamber to which the folds of the wire screen are attached, a cover of filtering material over all of said pockets, a cylindrical shell inclosing said filter, said shell having heads thereon with sleeves placed centrally on said heads, which sleeves engage with the collars on said filter and form a joint therewith.

5. An air filter having a serpentine strip of wire screen bent at both ends to form inwardly opening wedge shaped pockets, arranged radially around a cylindrical chamber, cylindrical collars at each end of said chamber to which the folds of the wire screen are attached, a cover of filtering material over all of said pockets, a cylindrical shell inclosing said filter, said shell having heads thereon with sleeves placed centrally on said heads, which sleeves engage with the collars on said filter and form a joint therewith, one of said sleeves opening outwardly and forming an exhaust for the filter.

6. An air filter having a serpentine strip of wire screen bent at both ends to form inwardly opening wedge shaped pockets, arranged radially around a cylindrical chamber, cylindrical collars at each end of said chamber to which the folds of the wire screen are attached, a cover of filtering material over all of said pockets, a cylindrical shell inclosing said filter, said shell having heads thereon with sleeves placed centrally on said heads, which sleeves engage with the collars on said filter and form a joint therewith, 110 washers surrounding each sleeve, spacing the filter from the adjacent head.

7. A filter having a series of outwardly opening pockets, a shell having openings therein in line with the openings in said pockets, the openings in said shell causing the air to enter each pocket centrally between the walls thereof, said filter being independent of and separate from the cylindrical shell.

8. An air filter having a cylindrical shell, openings through the cylindrical part of said shell arranged in parallel rows, a filter inside of said shell having outwardly opening 5 pockets in line with said rows of holes, said pockets being located radially to the axis of the cylinder, heads on the top and bottom of said shell, openings in the bottom head through which the dust can pass out of the shell.
9. An air filter having a cylindrical shell, openings through the cylindrical part of said shell arranged in parallel vertical rows, a filter inside of said shell having outwardly 10 opening vertical pockets in line with said

rows of holes, said pockets being located radially to the axis of the cylinder, heads on the top and bottom of said shell, openings in the bottom head through which the dust can pass out of the shell.

20

10. An air filter having a serpentine strip of wire screen bent to form inwardly opening wedge shaped pockets, arranged radially around a cylindrical chamber, cylindrical collars at each end of said chamber to which 25 the folds of the wire screen are attached, a cover of filtering material over all of said pockets.

In testimony whereof I affix my signature.
LEWIS L. DOLLINGER.
